UNITED STATES PATENT OFFICE.

GEORGE JOHNSON JERVIS, OF NEW YORK, N. Y.

CHILD'S BLOCK.

Application filed September 17, 1920. Serial No. 410,900.

To all whom it may concern:

Be it known that I, GEORGE JOHNSON JERVIS, a citizen of the United States of America, residing at New York, N. Y., have invented 5 new and useful Children's Blocks, of which the following is a specification.

My invention relates particularly to blocks for the instruction and amusement of children.

10 The main object is to provide a block or set of blocks suitable for the use of children, which are clean and safe to use, and unbreakable.

Another object is to provide a set of a few 15 blocks which are capable of being arranged in many different ways so as to suggest the outlines of many different articles, structures, animals, plants, etc.

The blocks are preferably formed of rubber, vulcanized so as to be medium hard. They 20 should be hard enough to keep their shape and withstand rough usage, and yet they should be soft enough so that they are not brittle and do not have edges which will cut 25 or scratch. It is also preferable that the consistency be such that the surface is somewhat adhesive or rough like that of an eraser, so that two blocks when placed together will not tend to slide on one another. The composition 30 may contain fiber if desired, or other substances commonly used in making rubber articles.

Fig. 1 shows a set of blocks with their preferred relative shapes and proportions.

35 Fig. 2 shows them arranged in the outline of a tower or lighthouse.

Fig. 3 shows them arranged in the form of a ship.

40 Fig. 4 shows them arranged in the form of an airplane.

Fig. 5 shows part of them arranged in the form of a submarine.

Fig. 6 shows them arranged in the form of a horse.

45 Fig. 7 shows part of them arranged in the form of a tree.

Fig. 8 is a perspective view of a single block.

The block 10 is preferably a trapezoid of

such shape and proportions as to constitute 50 one-half of a hexagon, so that the sides and top are of the same length. The block 11 is a right angle triangle whose two sides are of the same length as the sides and top of the trapezoid. The blocks 12 and 13 are similar 55 triangles, each being equal to one-half of the block 11. The block 14 is a rectangle whose length is preferably equal to the side of the trapezoid, and whose width is one-half its length. There may be two blocks 60 like 14 as shown in Fig. 2, or one of them may be divided into two parts 15 and 15' as shown in Fig. 1.

I have shown only a few of the many arrangements in which these blocks may be 65 used. By providing a plurality of sets in different colors, it is possible to produce a much larger variety of designs with contrasting colors.

The blocks being made of rubber are sub- 70 stantially unbreakable, and although they may have abrupt edges so as to be neat in appearance, they will not cut or scratch like stone or wooden blocks. They may be readily washed or cleaned without warping or 75 splitting. Being more or less soft, there is no danger of a person being injured by being struck with them. The size shown in Fig. 1, I have found to be a satisfactory size. Preferably none of the blocks is small 80 enough to be swallowed.

I claim:

A set of blocks for the amusement and instruction of children, comprising one block of trapezoidal outline, one block of 85 triangular outline having two sides each of which is approximately the same length as the side of the first mentioned block, two smaller triangular blocks each of which has a base approximately equal in length to the 90 length of a side of the first mentioned triangular block, and two rectangular blocks at least one of which has a length approximately equal to the length of the side of the first mentioned triangular block, and a 95 width of approximately half the same.

GEORGE JOHNSON JERVIS.
